CLAIM

The ornamental design for a foot arch support wrap, as shown and described.

DESCRIPTION

FIG. 1 is a top perspective view of a foot arch support wrap, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dot-dash broken lines represent stitching and form part of the claimed design.

1 Claim, 4 Drawing Sheets(56)
